STABILIZING APPARATUS

Lawrence B. Lynn, Wilkinsburg, Pa., assignor to
Westinghouse Electric Corporation, East Pitts-
burgh, Pa., a corporation of Pennsylvania

Original application November 23, 1940, Serial
No. 366,918, now Patent No. 2,381,161, dated
August 7, 1945. Divided and this application
September 11, 1944, Serial No. 553,521

4 Claims. (Cl. 60—52)

1

This application is a division of my application, Serial No. 366,918, filed November 23, 1940, maturing into Patent No. 2,381,161, granted August 7, 1945, relating to stabilizing apparatus constituting an improvement upon that disclosed and claimed in the patent of Hanna, 2,381,160, granted August 7, 1945.

In said patent of Hanna, a pair of valves connected by a balancing lever are moved to vary hydraulic pressures by means of a pair of electromagnets to which currents are supplied by resistors. The hydraulic arrangement, while having inherent positive stiffness (increasing displacement accompanied by an increasing opposing force), becomes unstable if the negative stiffness (increasing displacement accompanied by decreasing opposing force) due to the electromagnets overcomes the positive stiffness. Hanna proposed to vary the currents in the circuits differentially by having a fixed resistor in one circuit and a variable resistor in the other, the variable resistor having contacts tapped therealong. If the resistor resistances in circuit are equal with half of the variable resistor shunted, it will be apparent that the currents in the circuits may be varied differentially by engaging and disengaging contacts so that the variable resistor may be adjusted to provide resistance in one circuit which is more or less than the fixed resistance in the other circuit; however, this arrangement has the disadvantage of a high negative stiffness because of the relatively large total currents required for operation, and, in consequence of this, the hydraulic apparatus has to be designed to give sufficient positive stiffness for stability.

In accordance with my invention, the two circuits supplying the electromagnets are each provided with a resistor, each resistor has contacts tapped therealong, and the two groups of contacts are arranged parallel with an actuator interposed therebetween. If the actuator is moved away from mid position in one direction, the contacts of one group are progressively engaged; if it is moved away from mid position in the other direction, the contacts of the other group are progressively engaged; and if it is moved toward mid position, then engaged contacts are thereby progressively disengaged. Preferably, with the actuator in mid position, a plurality of contacts of each group are engaged, whereby, with movement of the actuator away from mid position, the engaged contacts of one group will be progressively disengaged and additional contacts of the other group will be progressively engaged, although the contacts and actuator may be so ar-

2

ranged that, with the latter in mid position, all of the contacts are disengaged. Either type of "push-pull" arrangement has the advantage of a smaller average flux density in operating the electromagnetically-operated valves, with the result that the negative stiffness is reduced, for it will be apparent that the total currents required will be relatively less than necessitated in the Hanna arrangement. Therefore, with the reduced negative stiffness, the hydraulic apparatus may be designed for relatively less total stiffness with the result that component parts may be made smaller.

The currents supplied to the magnet windings should be such as to obtain maximum sensitivity from the stabilizer without causing the gun to hunt or vibrate. Insufficient current causes a loss of sensitivity. On the other hand, too much current supplied to the windings increases the sensitivity to the extent that the gun will vibrate rapidly. Therefore, to assure of current supply in relation to positive stiffness of the hydraulic arrangement such that maximum sensitivity may be secured without hunting or vibration, I prefer to incorporate a stiffness rheostat or potentiometer between the source of current supply and each of the circuits supplying the magnet windings. With the "push-pull" arrangement of contacts and actuator, the total currents required for operation of the electromagnets may be minimized; and, by adjusting the rheostat or potentiometer means supplying the circuits, the currents for the electromagnets may be adjusted to give a negative stiffness having such relation to the inherent positive stiffness that the stabilizer may have maximum sensitivity without hunting or vibration.

An object of the invention is to provide, in connection with apparatus of the above character, an arrangement of resistors, contacts, and an actuator for the contacts such that the currents supplied to the electromagnets for operating the magnetic valves may be varied differentially in opposite directions in such a manner that the total currents required may be minimized in order to reduce the negative stiffness occasioned by the employment of electromagnets.

A further object of the invention is to provide, in connection with the improved arrangement of resistors, contacts and actuator, stiffness rheostats or potentiometers for supplying currents to the magnet circuits so that such a relation of negative stiffness to positive stiffness may be had that the stabilizer has a high degree of sensitivity with preservation of stability of operation.

Other objects and advantages will become more apparent from a study of the following specification when considered in conjunction with the accompanying drawings, in which:

Fig. 1 is a perspective view of a gun and its mounting with stabilizing apparatus applied thereto;

Fig. 2 is a schematic view showing partly in cross section an electrically-controlled hydraulic system involving principles of my invention;

Fig. 3 is a perspective view of gyroscopic apparatus used to control the system of Fig. 2; and

Fig. 4 is a detail sectional view of a damper for the gyroscopic apparatus.

Referring to the drawings in more detail, there is shown a gun or body member 5 having trunnions 6 mounted in bearings 7 carried by the frame structure 8 connected to a tank or supporting body, portions of the latter being fragmentarily shown at 9. Stabilizing apparatus cooperates with the gun or body member to stabilize the latter about the trunnion axis to minimize angular deviations of the gun about that axis from aimed position and due to disturbances. Such apparatus provides for movement of the tank body about the trunnion axis and it is adjustable in a follow-up manner to provide for changes in elevation.

The stabilizing apparatus includes a hydraulic motor device, at 10, connecting the gun or body member and the supporting structure or tank, the motor device including a cylinder 11 and a piston 12 in the cylinder and dividing the latter into pressure chambers 13 and 14. A pair of pumps 15 and 16 driven by a motor M have their outlets opening into pressure spaces which include the chambers 13 and 14. More particularly, the pumps have their outlets 17 and 18 connected by passages 19 and 20 to the pressure chambers. By-pass passages 21 and 22 communicate with the passages 19 and 20 and they are provided with outwardly-facing valve seats 23 and 24 with which cooperate valves 25 and 26 connected by a balancing lever 27 fulcrumed at 28. It will be apparent that, if either valve is moved in a closing direction, the liquid pressure in the corresponding pressure space will increase and vice-versa. The liquid pressure in each pressure space exerts force on its valve tending to open it; and, as the valves are connected by the balancing lever, not only does the fulcrum of the latter oppose the resultant of the opening forces acting on the two valves, but the oppositely-acting moments of such forces tend to be equalized by the lever. Movement of the lever from an equilibrium position is opposed by increasing resistance because of the increasing differential of fluid pressure forces acting on the valves. Therefore, so far as the valve tend to be positioned by fluid pressures, the hydraulic arrangement has positive stiffness, increase in displacement or deviation being accompanied by increasing opposing force.

From the structure so far described, it will be apparent that the pressures in the chambers 13 and 14 acting differentially on opposite sides of the piston 12 may be controlled by adjusting the valves 25 and 26 by moving one valve in a closing direction and the other valve in an opening direction. Therefore, if controlling forces of proper magnitudes are applied to properly timed relation to the valves, hydraulic pressures may be developed such that the force differential thereof acting on the motor device, at 10, results in application by the latter to the gun of stabilizing force. In other words, disturbing torque acting on the

gun about the trunnion axis is accompanied by the prompt developing of an opposing stabilizing torque effective thereon about the same axis. Furthermore, as liquid from a contracting cylinder space may at all times escape through the corresponding by-pass, it will be apparent that the tank or supporting structure is capable of moving angularly about the trunnion axis relative to the gun, whereby the tank is free to follow the terrain without thereby acting through the stabilizer to disturb substantially the aimed position of the gun.

The controlling forces applied to the valves are developed in response to angular displacement or deviation of the gun about the trunnion axis and to the velocity of such displacement or deviation. The provision for control in response to velocity assures of a strong opposing force effective as displacement begins; and the provision of means responsive to gravity, and by means of which angular displacement may be sensed, provides for control so that the gun or body member tends to return to the aimed or wanted position. The displacement-sensing and the velocity-sensing means work together to effect stabilization of the aimed position, the major part of the stabilizing effort being developed in response to the velocity-sensing means and the latter cooperating with the datum or gravity-responsive means to secure return with a minimum of hunting, the velocity-sensing means acting in an anticipatory manner to oppose departure from the wanted or aimed position and in an anti-hunting manner to oppose return to that position, the displacement and velocity effects acting jointly on the hereinafter-described control device to obtain resultant forces or effects for controlling the stabilizer.

Referring now to the displacement and velocity sensing components, there is shown a supporting plate 30 connected to move with the gun as the latter moves angularly about the trunnion axis. The supporting plate carries a gravity-responsive element, for example, the pendulous member 31 having a supporting pivot 32. A pendulous gyro 33 is operative so that its spin axis seeks the vertical and its cooperates with the pendulous member 31 to stabilize the latter with respect to the vertical plane of the pivot axis of the pendulous member.

The velocity-sensing means comprises a second gyro 34 carried by the supporting plate 30 so as to precess when the latter moves angularly with the gun about the trunnion axis. The gyro 34 is a neutral one and it includes a casing or frame 35 having a spinning body 36 journaled therein and the casing is pivotally connected, at 37, 37, to upper and lower arms 38, 38 of yoke 39 attached to the plate 30. The gyro is arranged with its axis of spin x-x extending transversely of the mounting axis of the supporting plate 30 and its precession axis y-y, defined by the axis of the pivots 37, 37, extending normally both to the spin axis and to the mounting axis. Therefore, if the gun moves, the gyro will have precessional movement which is proportional to velocity of angular movement of the gun. A damper, at 34a, connecting the supporting plate and the gyro so as to be effective about the precession axis of the latter, serves to filter out undesired vibratory effects so that the gyro is maintained responsive to the disturbance which it is intended to sense.

The controlling device, at 40, which is jointly operated in response to the pendulous member

31 and the velocity gyro 34, comprises an actuating part 41 movable with the gyro 34 when the latter moves about the precession axis $y-y$ and an actuated part 42 carried by the pendulous member. As the supporting plate carries the 5 gravity-responsive means or pendulous member 31, the velocity gyro 34, and the actuating and actuated components of the control device, at 10 40, it constitutes the means by which displacement and velocity may be utilized in effecting relative movements of the components of the control device such that the desired resultant controlling effects may be delivered from the latter.

As shown, the actuated part 42 comprises self-opening leaf spring contacts 43 arranged as parallel groups 44 and 45 and the actuating part 41 includes an insulating actuator 46 arranged between the groups of contacts and which operates, as it moves from mid position in one direction, to progressively engage the contacts of one group; as it moves from mid position in the other direction, to progressively engage the contacts of the other group; and as it moves toward mid position, it progressively disengages engaged contacts. Preferably, for reasons hereinafter given, the arrangement is such that, with the actuator in mid position, a plurality of contacts of each group are engaged.

While the contacts may be used to vary any suitable impedance devices, they are shown as being tapped along resistors, the group of contacts 44 being tapped along the resistor 47 and those of the group 45 being tapped along the resistor 48, and the resistors 47 and 48 are arranged in circuits 49 and 50 including windings 51 and 52 of a pair of electromagnets used for applying forces to the poppet valve aggregate. As the contacts of the group 44 are progressively engaged, successive portions of the resistor 47 are shunted to increase the current in the circuit 49 and to increase the flux of winding 51; and, as the contacts of the group 45 are progressively engaged, the current in the circuit 50 is increased to increase the flux of the winding 52.

With the two poppet valves 25 and 26 interconnected by the balancing lever mechanism, both valves are normally open because of normal equal energization of the windings 51 and 52, the magnetic forces exerted by the windings on the balancing lever mechanism being balanced and consequently such valves occupying a balanced mid position.

Assuming that the right-hand resistor 47 has been partially shunted by the contacts of the group 44 due to relative movement of the actuating element 46 and the actuated element 42 as the result of rocking movement of the supporting plate 30, it will be seen that more current will flow through the coil 51 due to the decrease of resistance in series therewith, than through the coil 52; and, as a result, the balancing lever 27 will move in a counterclockwise direction which will result in movement of the lower valve 26 in a closing direction and further opening of the upper valve 25. As a consequence of this, the pump 16 will build up pressure in the pressure space, including the passage 20 and the cylinder chamber 14, and thereby bring about an increase in pressure in the lower part of the cylinder which will exert upward force on the piston 12 therein so as to push upward on joint 55, which is secured to the gun 5, to apply a clockwise stabilizing torque to the gun about the axis of its trunnions 6.

If, on the other hand, the displacement were

in the opposite direction so that the left-hand resistor 48 were shunted, coil 52 would be energized to a greater extent than coil 51, causing movement of the upper valve 25 in a closing direction and building up of pressure in the pressure space including the conduit 19 and the cylinder pressure chamber 13, the increased pressure above the piston 12 resulting in counterclockwise stabilizing torque applied to the gun 5 about its trunnion axis.

The hydraulic pressures in the stabilizer cylinder 11 are controlled by their respective valve currents. As the currents and magnetic flux densities are increased, negative stiffness is also increased. Regarding the definition of stiffness, a body is said to have positive stiffness if displacement is opposed by increasing resistance, as with a spring where increase in displacement is accompanied by increase in force. An electromagnet has negative stiffness, since, as the armature is attracted towards the core, the magnetic pull increases. If the poppet valves of the valve aggregate be considered to the exclusion of the magnets, it will be apparent that the liquid pressure forces acting on the valves cause the aggregate to seek a position placing such forces in equilibrium and that displacement from equilibrium position is accompanied by increasing opposing force (positive stiffness). Disregarding the valves and considering only the magnets, instead of the displacement being accompanied by increasing opposing force, the force tends to increase the displacement (negative stiffness). Since the magnets act in opposition, it will be obvious that, for the same differential force, a greater total current and, therefore, greater total flux, will be required where a fixed current flows through one magnet and the current through the other is caused to vary above and below the first (Hanna, aforesaid,) than is required in the present arrangement where both currents are varied. The present arrangement is capable of exerting the same force as that of Hanna, aforesaid, with less aggregate current and therefore less magnetic flux; and, since the negative stiffness is a function of flux, it being remembered that the force exerted by a magnet on an armature varies directly as the flux and inversely as the square of the distance, it will be apparent that the negative stiffness is reduced.

If such negative stiffness becomes greater than the positive stiffness arising from the hydraulic pressures acting on the valves, unstable operation occurs. The range of instability may be varied by changing the valve clearances, air gaps or other constants, and may be kept low by keeping the total valve currents at a minimum.

Valve operation with a fixed current in one coil and a variable current in the other, as described in the aforesaid Hanna patent, requires rather substantial flux densities so that the range of unstable operation is appreciable.

By reducing the current in one valve operating electromagnetic coil as the current in the other coil is increased (class A push-pull), the average flux is reduced and stability is improved.

Another method of operation comprising the provision of two sets of contacts, one on the right hand and the other on the left hand of the 70 actuating member and with all of the contacts normally in open position with the actuator in mid position. This type of operation (class B push-pull) further reduces the average flux density and greatly improves stability.

75 Push-pull operation, such as involved in either

7 class A or class B described above, on the gun stabilizer has been obtained by employing two groups of contacts as shown in Fig. 2 and related to the actuator so that, with the latter in mid position, a plurality of contacts of each group are engaged.

A change in angular position of the gun 5 about the axis of the trunnions 6 causes more leaves of one group of contacts to be closed or fewer of the other to be closed, or both. By choice of width of the actuating member 46, it is possible to obtain any of the several classes of push-pull operation. Class A appears to be preferable, since the contacts are immediately responsive to the slightest movement of the actuator from its mid position.

It is desirable to have equal increments of corrective torque for equal increments of angular displacement of the gun. As applied to the gun stabilizer, for example, fifteen leaves of the contacts may close for one degree angular displacement of the gun, or one leaf for each four minutes. The pressures as controlled by the valves are approximately proportional to the square of the valve currents, being distorted by pump characteristics and other factors. Actual graphs of corrective torque against valve current were obtained by measurement on a full scale model gun and stabilizer. From these, the currents to produce uniform steps of torque were determined, and resistance steps (of unequal values) to give these currents calculated. Resistors 47 and 48 were made in steps of these values and connected to their respective groups of contact leaves.

Thus a linear relation between angular gun displacement and restoring torque is obtained. The rate of change of torque to displacement, or the stiffness of the stabilizer, is determined by the voltage applied to the circuit and may be varied by resistance means, such as rheostats or potentiometers 57 and 58. Such rheostat or potentiometer means may provide for independent adjustment of each coil actuating circuit and assures of currents being supplied to the circuits such that the negative stiffness exerted on the valve aggregate will be in such relation to the positive stiffness thereof that the apparatus may be adjusted so as to be adequately sensitive and so as to avoid hunting.

During recoil following firing of the gun, excessively large unbalancing torques exist because of the displacement of the center of gravity to a position to the rear of the trunnion axis for periods of about one-half second. Because of these unbalancing effects occurring only after each shot and persisting for relatively short periods, and because of space and weight limitations imposed, it is undesirable to build the stabilizer large enough to accommodate these large disturbances, which are many times the magnitude of the disturbances transmitted to the gun due to motion of the tank or vehicle.

I avoid the necessity of building such a large stabilizer as would be necessary in the system shown and claimed in the aforesaid Hanna patent by supplying a high current to a valve coil during recoil to couple the gun closely to its mount during this period of unbalance. As more particularly disclosed and claimed in my patent aforesaid of which the present application is a division, the high value current may be supplied by an additional voltage applied to the coil circuit by the auxiliary coil 60 through a switch 61 operated by the motion of the gun undergoing recoil. In this manner, additional energization

is provided which tends to close the lower poppet valve 26, resulting in building up of pressure in the cylinder space 14 below the piston 12 and which counteracts the pressure created by downward movement of the piston as a consequence of recoil unbalance of the gun. A check valve 62, normally biased to its closed position by a spring, may be provided for the purpose of preventing the backward flow of liquid through the pump 10 when the pressure created by the downward movement of the piston becomes in excess of the peak delivery pressure of the pump. Therefore, having cared for recoil in this particular manner, the stabilizer and its control may be designed to meet stabilizing requirements necessitated because of motion of the vehicle or tank.

From the foregoing, it will be apparent that I have provided, for any suitable regulating apparatus having a controlling member which operates with inherent positive stiffness, a pair of electromagnets for moving the controlling member in opposite directions, together with means for controlling the electric currents required to energize the magnets so that such currents may be kept sufficiently small to avoid the negative stiffness introduced because of the magnets from overcoming the inherent positive stiffness and thereby bring about unstable operation of the apparatus. On the other hand, sensitivity of the apparatus is increased by increasing the currents and, therefore, negative stiffness. Therefore, the problem arises of providing the sensitivity desired without instability; and, it is for this reason, that rheostat or potentiometer 30 means is provided for varying the currents supplied to the circuits having the resistors and the flexible contacts. Such rheostat or potentiometer means makes it possible to overcome individual variations in positive stiffness of regulators, the desired sensitivity and stability in each case being secured by rheostat or potentiometer adjustment.

While the invention has been shown in but one form, it will be obvious to those skilled in the art that it is not so limited, but is susceptible of various changes and modifications without departing from the spirit thereof.

What is claimed is:

1. In apparatus for controlling a hydraulic 50 motor so that the latter drives a pivotally-mounted body about its mounting axis in such manner as to stabilize the body by minimizing oscillatory disturbances of the latter with respect to such axis, said apparatus including a pair of passages 55 respectively supplied with liquid from a pair of pressure-developing devices and supplying liquid to said motor; each of said passages having an escape port whose discharge end is formed as a valve seat; valves movable toward and away from the seats to vary the pressures in the passages; a balancing rocker fulcrummed at an intermediate point and having its ends connected to the valves so that opening liquid pressure forces act continuously on the latter and on the rocker with the moments of such forces about the fulcrum axis in opposed relation, whereby there is provided a positive stiffness effect adequate for stability of the apparatus; a pair of electro-magnets for applying controlling forces to the rocker with the 60 moments of such forces about the fulcrum axis in opposed relation and with the differential of the moments of liquid pressure forces normally balancing the differential of the moments of controlling forces; and means for energizing said magnets so that change in the differential of

9 moments of the controlling forces causes the rocker and the valves to move to change the differential of moments of the liquid pressure forces until the balanced relation of moments is re-established and so that the negative stiffness effect of the magnets is maintained sufficiently less than said positive stiffness effect for operation of the apparatus with adequate sensitivity; said last-named means comprising a pair of circuits with the windings of the electro-magnets included in the respective circuits, a resistor in each circuit, self-opening leaf spring contacts tapped along each resistor and arranged to be progressively engaged to shunt successive portions of the resistor and to be progressively disengaged to include such portions in circuit, said contacts being arranged as a pair of parallel groups, and an actuator interposed between the groups of contacts and movable away from mid position, in one direction, to progressively engage the contacts of one group and, in the other direction, to progressively engage the contacts of the other group and movable toward mid position to provide for disengagement of engaged contacts.

2. Apparatus as claimed in claim 1 wherein a plurality of contacts of each group are held closed by the actuator when the latter is in mid position.

3. Apparatus as claimed in claim 1 with variable resistance means for varying the current supplied from a suitable source to each of the circuits.

4. Apparatus as claimed in claim 1 with a pair of variable resistances arranged in the respective circuits between a suitable current source and said resistors.
